(57) CLAIM

The ornamental design for leggings, as shown and described.

DESCRIPTION

This application is related to U.S. application Ser. No. 29/656,262, filed Jul. 11, 2018, entitled "Leggings," and, U.S. application Ser. No. 29/656,275 filed Jul. 11, 2018, entitled "Leggings," both of which are concurrently filed herewith, and the disclosures all of which are incorporated herein by reference.

FIG. 1 is a front perspective view of leggings according to our new design;

FIG. 2 is a front elevation view thereof;

FIG. 3 is a rear elevation view thereof;

FIG. 4 is a right side elevation view thereof, the left side being a mirror image thereof; and,

FIG. 5 is an enlarged view of the section shown in FIG. 1. The broken lines shown in the drawings are for the purpose of illustrating portions of the leggings that form no part of the claimed design.

1 Claim, 5 Drawing Sheets
